UNITED STATES PATENT OFFICE.

GEORGE EZRA MORTON LEWIS, OF TRURO, CANADA.

VENEER-CUTTING MACHINE.

SPECIFICATION forming part of Letters Patent No. 609,513, dated August 23, 1898.

Application filed August 9, 1897. Serial No. 647,544. (No model.)

To all whom it may concern:

Be it known that I, GEORGE EZRA MORTON LEWIS, a British subject, residing at Truro, in the county of Colchester, in the Province 5 of Nova Scotia and Dominion of Canada, have invented certain new and useful Improvements in Veneer-Cutting Machines, of which the following is a specification.

My invention relates to improvements in 10 veneer-cutting machines in which the bolt of wood from which the veneer is cut is revolved in continuous contact with a cutting-knife, whereby a connected thin spiral sheet is severed from the revolving wood; and the objects 15 of my invention are, first, to provide means whereby curved veneers may be cut, and, second, to provide means by which a curved or straight veneer can be cut and chamfered on either one or both edges to a desired bevel 20 by the simultaneous use of different knives. I attain these objects by the mechanism illustrated in the accompanying drawings, in which—

Figure 1 is a face elevation of an ordinary 25 veneer-cutting knife-block embodying my invention. Fig. 2 is a vertical section of the same on line *a b*, looking in the direction of the arrow and showing a portion of a revolving veneer-bolt in a position for cutting into 30 veneers. Fig. 3 is a partial section on line *c d* of Fig. 2, looking toward the face of the knife-block and having the chamfering-knives removed. Fig. 4 is a disconnected 35 plan of a curved presser-bar, a curved cutting-knife, and the chamfering-knives in place. Figs. 5 and 6 are edge views of the chamfering-knives.

Similar letters refer to similar parts throughout the several views.

40 In the drawings, *A* is the cast-iron knife-block ordinarily used in veneer-cutting machines.

a is the body of a curved cutting-knife, which is secured to the knife-block *A* by the 45 adjustable bolts *c c c*.

b is a curved steel knife-blade which is riveted onto the knife-body *a* and is used especially for cutting curved veneers. In Fig. 1 the corners of this knife are broken away, 50 showing the chamfering-knives in place.

d d are two chamfering-knives which are inserted in the slots *e e* (shown in Fig. 3) in the knife-block *A* and are adjusted by means

of set-screws, one of which is shown at *f* in Fig. 2.

55

i i are the blades or cutting parts of the chamfering-knives, which are formed to chamfer any bevel desired.

g is the presser-bar, which is curved at the 60 face edge to correspond with the curved knife-blade *b* and is set at a distance from the curved knife-blade *b* corresponding to the thickness of the veneer required.

B is a clamp which holds the presser-bar *g* and the chamfering-knives *d d* rigidly in 65 place. This clamp is pivoted at *P*, and its pressure upon the presser-bar *g* is controlled by the set-screw *Q*, which passes through the outer end of the knife-block *A*.

C is a portion of a veneer-bolt, showing its 70 relative position to the knives and presser-bar while being operated upon.

In Fig. 4 the curved presser-bar *g*, the curved cutting-knife blade *b*, and the chamfering-knives *d d* are shown in their relative 75 position to each other as they would appear in a plan view, the space *x* representing a section of a veneer as it would appear after being cut by a curved knife and chamfered on both edges by the chamfering-knives *d d*.

80

When the machine is in operation, the veneer-bolt *C* is revolved against the cutting edge of the knife-blade *b*, which is automatically fed toward the bolt *C*, as required, the severed veneer passing through between the 85 knife-blade *b* and the presser-bar *g*, when it then comes in contact with the blades *i i* of the chamfering-knives *d d*, where it is chamfered to the desired bevel.

What I do claim, and desire to secure by 90 Letters Patent, is—

In a veneer-cutting machine, the knife-block, and a curved knife-blade secured thereto, combined with the knife-block provided with grooves *e*, the pivoted clamp, the 95 screw *Q*, the presser-bar *g* held in position by the clamp, the two chamfering-knives placed in grooves in the block *A* and held in position by the presser-bar, and the screws *f* for adjusting them, substantially as shown 100 and described.

GEORGE EZRA MORTON LEWIS.
